UNITED STATES PATENT OFFICE.

WILLIAM ALEXANDER MOORE, OF NEW YORK, N. Y.

RAILROAD-TIE.

No. 796,140.

Specification of Letters Patent.

Patented Aug. 1, 1905.

Application filed March 15, 1905. Serial No. 250,144.

To all whom it may concern:

Be it known that I, WILLIAM ALEXANDER MOORE, of the city, county, and State of New York, have invented a new and Improved Railroad-Tie, of which the following is a full, clear, and exact description.

My invention relates to improvements in railroad-ties and in means for fastening a railway-rail to the tie.

The object of my invention is to produce a metallic tie which is very simple and cheap, which can be rolled out to the requisite shape by ordinary rolling-mills, which is constructed so as to be particularly strong, which is adapted to support a rail of usual construction, which is also built in such a way that it can be embedded in the road-bed and the latter will have firm grip on the tie, so as to prevent its displacement, and which has a very convenient and secure means for fastening a rail to it.

With these ends in view my invention consists of certain features of construction and combinations of parts, which will be herein-after described and claimed.

Reference is to be had to the accompanying drawings, forming a part of this specification, in which similar figures of reference indicate corresponding parts in all the views.

Figure 1 is a broken plan view of my improved tie, showing a rail in place on two adjacent sleepers. Fig. 2 is a view, partly in elevation and partly in cross-section, of two sleepers or ties with the rail attached; and Fig. 3 is a broken detail perspective view showing particularly the rail-fastening clip and the means for securing it in place.

The cross-tie or sleeper has necessarily a flat top surface 10, on which the rail rests, and has, preferably, vertical sides 11, which merge into the foot-flanges 12. This structure is preferably made, as described and as shown best in Fig. 2, with the raised central portion of the tie of rectangular cross-section, because this is easy to roll and it is particularly strong. Moreover, it will be seen that the foot-flanges 12 are embedded in the road-bed, as is the greater part of the body portion of the tie, while the hollow part of the tie can also be filled with the ballast of the road-bed, and so the tie is very secure. However, the sides 11 can be more or less inclined without particularly affecting the principle of the invention. The structure shown gives a very firm seat for the rail 13, which is of the usual or any preferred shape, and the rail is held in

place by the fastening-clips 14, which are of metal and which are adapted to fit flat on the tie-top and have raised portions 14^a, which fit over the rail-flanges and against the rail-web, as shown clearly in Figs. 1 and 2.

To provide for conveniently and securely fastening the clip 14, each clip has a bolt-hole 15, which is a little off the center and which is adapted to receive the bolt 16, and this has the customary head and a squared portion 16^a on its shank, which squared portion is adapted to fit in the narrow part 17^a of the bolt-hole 17, which is produced in the top of the tie 10, these elongated holes 17 17^a being made, preferably, parallel with the rail. To fasten the parts together, the bolt is placed in the hole 17 and the squared part 16^a pushed into the slot 17^a of the hole, while the body portion of the bolt is pushed up through the hole 15 in the clip 14. This arrangement brings the part 14^a against the flange and web of the rail, and when the nut is applied to the bolt-top, as in Fig. 2, the rail clip and tie are all securely fastened together. To provide against any accidental loosening of the parts and to prevent the bolt 16 from creeping by any possibility into the larger part of the hole 17, the clip has on its under side a boss or stop 14^b, which can be conveniently punched down in the clip, as shown in Fig. 2, and this boss or stop striking the wall of the hole 17 holds the clip securely against any lateral slipping. I have shown a small boss or stop 14^b; but, if desired, it can be made large enough to practically plug the hole 17. The clip 14 can be removed by loosening the nut on the bolt 16 enough to let the boss 14^b slip over the edge of the hole 17, when the clip and bolt can be slid till the bolt can be withdrawn through the perforation 17, and the replacing of the clip can be accomplished with as much ease.

From the foregoing description it will be seen that the tie can be easily laid in the road-bed, the rails conveniently applied to the tie, and that the fastening-clips and bolts can be placed in position very quickly and easily, and that when positioned and fastened, as shown, they hold the rail securely.

Having thus fully described my invention, I claim as new and desire to secure by Letters Patent—

1. The combination with the hollow tie having holes therein, the said holes merging into slots, said slots extending parallel with the rails, of the clips shaped to fit a rail-flange,

a bolt to extend through the clip and the slot, and a boss on the clip to enter the hole and engage the wall thereof at a point opposed to the slot.

2. The combination with the hollow tie having holes therein, the said holes merging into slots, said slots extending parallel with the rails, of the clips shaped to fit a rail-

flange, a bolt to extend through the clip and having a squared portion to enter the slot, and a boss on the clip to engage the wall of the hole at a point opposed to the slot.

WILLIAM ALEXANDER MOORE.
